John J. Morse.

UNITED STATES PATENT OFFICE.

JOHN J. MORSE, OF ADRIAN, MICHIGAN.

TIE FOR WIRE FENCING.

No. 799,921.

Specification of Letters Patent.

Patented Sept. 19, 1905.

Application filed February 27, 1905. Serial No. 247,432.

To all whom it may concern:

Be it known that I, JOHN J. MORSE, a citizen of the United States, residing at Adrian, in the county of Lenawee, State of Michigan, 5 have invented certain new and useful Improvements in Ties for Wire Fencing; and I do declare the following to be a full, clear, and exact description of the invention, such as will enable others skilled in the art to which it applies 10 to make and use the same, reference being had to the accompanying drawings, and to the figures of reference marked thereon, which form a part of this specification.

This invention relates to a knot or tie for 15 wire fencing; and it consists in the peculiar formation hereinafter set forth, and pointed out particularly in the claims.

The object of the invention is to provide a tie for uniting the crossed strands of a wire 20 fencing or fabric of such shape as to enable it to be readily driven in suitable dies to form it around said wires and firmly join said strands at their point of intersection, said tie being of compact formation, requiring but a comparatively short length of wire to form it. 25

The above object is attained by the structure illustrated in the accompanying drawings, in which—

Figure 1 is a perspective view of a tie involving my invention. Fig. 2 is a plan view thereof. Fig. 3 is a side elevation of Fig. 1. Fig. 4 is an end elevation. Fig. 5 is an inverted plan.

Referring to the characters of reference, 35 1 designates the longitudinal or strand wire and 2 the cross or stay wire of the fencing, which are crimped at their point of crossing, as shown at 3 in Fig. 1, to prevent lateral displacement, as is common.

The tie-wire which unites the crossed strands 40 of the fabric is preferably in the form of a staple which is driven into place upon the crossed wires by means of suitable dies (not shown) which embrace said wires and direct 45 the legs of the tie or staple to form the knot, as illustrated herein.

In the operation of driving the tie it is caused 50 to enter the dies so that the loop 4 of the staple will lie across the strand-wire and the legs 5 and 6 will be directed under or in the rear of the stay-wire. After passing in the rear of the stay-wire leg 5 is directed upwardly over the strand-wire, as shown at 7, its terminal portion 8 curving across the strand-wire 55 diagonally and entering between the inner side of leg 6 and the strand-wire between the stay-

wire and the loop end of the tie. The leg 6 after passing in the rear of the stay-wire is directed under the strand-wire beyond said stay-wire, as shown at 9, its terminal portion 60 being formed into an eye 10 around the strand-wire, which crosses said strand-wire obliquely and stands approximately parallel with the terminal portion 8 of leg 5.

It will be noted that the terminal portions 65 of the legs cross the strand-wire from the same side and extend in the same direction and that said terminal portions do not cross each other nor conflict in any way during the operation of forming the tie, an arrangement 70 which reduces the frictional resistance in driving the staple to the minimum, at the same time producing a tie which firmly unites the strands of wire and securely fastens itself in position thereon without leaving any protruding ends. 75

Having thus fully set forth my invention, what I claim as new, and desire to secure by Letters Patent, is—

1. In a tie for wire fencing, the combination 80 with the crossed strand and stay wires, of the tie in the form of a staple having its loop end crossing the strand-wire, its legs passing in the rear of the stay-wire, the terminal of one leg passing upwardly and diagonally across 85 the strand and stay wires in the direction of said loop, the end portion of said leg bending downwardly between the side of the opposite leg and the strand-wire, the terminal of said opposite leg passing under the strand-wire 90 and formed into an embracing-eye around said wire, said eye standing obliquely across the strand-wire approximately parallel with the terminal of said first-mentioned leg. 95

2. In a tie for wire fencing, the combination 100 with the strand and stay wires crimped at their point of crossing, of a tie-wire comprising a staple, having its loop end crossing the strand-wire at one side of the stay-wire, its legs passing in the rear of the stay-wire, one 105 leg curving upwardly and backwardly toward the loop end of the staple, crossing the strand and stay wires obliquely, the other end of the staple passing under the strand-wire and curving backwardly thereover to form an embracing-eye whose terminal portion stands in the plane of that part passing under the strand-wire and approximately parallel to the curved terminal portion of the first-mentioned leg. 110

3. In a tie for wire fencing, the combination with the strand and stay wires crimped at

their point of crossing, of a tie-wire comprising a staple having its loop end crossing the strand-wire at one side of the stay-wire, one leg of the staple passing in the rear of the stay-wire and curving upwardly and rearwardly over the strand-wire at the point of crossing of said strand and stay wires, the extreme end of said leg being bent downwardly into the angle between said wires, the other leg of the staple passing around the downwardly-bent end of said first-mentioned

leg and crossing under or in the rear of both the stay and strand wires obliquely thereto, the end portion of said last-mentioned leg being formed into an eye around the strand-wire which crosses said wire obliquely. 15

In testimony whereof I sign this specification in the presence of two witnesses.

JOHN J. MORSE.
